UNITED STATES PATENT OFFICE.

JOSEPH RICHARDSON WHITE, OF ST. JOSEPH, MISSOURI.

APPAREL-DRAWERS.

SPECIFICATION forming part of Letters Patent No. 656,916, dated August 28, 1900.

Application filed September 7, 1899. Serial No. 729,726. (No model.)

To all whom it may concern:

Be it known that I, JOSEPH RICHARDSON WHITE, of St. Joseph, in the county of Buchanan and State of Missouri, have invented 5 new and useful Improvements in Drawers, of which the following is a full, clear, and exact description.

This invention relates to drawers for women, and is distinguished particularly by a waistband separable in whole or in part from the rest of the garment and capable of being worn under the corset without interfering with the unrestricted use of the garment by the wearer.

This specification is the disclosure of several 15 forms of my invention, while the claim defines the actual scope thereof.

Reference is to be had to the accompanying drawings, forming a part of this specification, in which similar characters of reference indicate corresponding parts in all the views.

Figure 1 is a rear view of the garment with the waistband separable only at the back. Fig. 2 is an enlarged rear view showing the rear part of the garment separated from the 25 waistband. Fig. 3 is an enlarged side view of the garment, and Fig. 4 is a side view showing a form of the invention in which the waistband is wholly separable from the garment.

As shown in Figs. 1, 2, and 3, the garment 30 has a waistband formed of a front section *a* and a rear section *a'*, the former being narrower than the latter and the band being split at the right-hand side, the front part having buttons *b* and the rear part having 35 holes *b'*, engaging the buttons, to connect the two parts of the band. The rear part *a'* of the band may, if desired, be provided with a slit *a''* and laced at this point to facilitate regulating the size of the band.

40 The body of the garment is provided at each side with slits *c*, forming a rear or back flap *c*, provided with buttonholes *c'*, engaging buttons *c''* on the part *a'* of the waistband. With this construction the rear flap *c* may be con-

nected with the waistband, as shown in Fig. 45 1, or disconnected, as shown in Fig. 2, without in any way affecting the position or necessitating the movement of the waistband. The position of the waistband on the person's body being thus a permanent one, the waistband 50 may be worn under the corset and the outer dress of the wearer fitted nicely to the figure.

Should it be desired to construct the waistband wholly separable from the other part of the garment, the upper front part *d* of the body of the garment may be provided with buttonholes *d'*, engaging buttons *d''* on the front part *a* of the waistband. In other respects the construction described above would not be departed from.

60 It should be understood that my invention is not limited to the details of construction herein shown. For example, fastening devices other than the described buttons and holes may be employed without departing 65 from the essentialities of the garment.

Having thus described my invention, I claim as new and desire to secure by Letters Patent—

A garment, having a body and a waistband, 70 the latter lying snugly around the waist of the wearer, with its upper portion beneath the corset, and the body of the garment being formed at each side with approximately-vertical slits producing a rear flap, the upper 75 edge of the rear flap terminating at the lower edge of the waistband, so as to leave said flap free of the corset and permit the flap to be released without disturbing the waistband, and fastening devices for removably joining the 80 upper edge of said rear flap to the rear portion of the lower edge of the waistband, as described.

JOSEPH RICHARDSON WHITE.
